UNITED STATES PATENT OFFICE.

REUBEN SLOTE, OF MOUNT VERNON, NEW YORK.

BELT BUCKLE.

Application filed August 31, 1923. Serial No. 660,388.

To all whom it may concern:

Be it known that I, REUBEN SLOTE, a citizen of the United States, and a resident of Mount Vernon, in the county of Westchester 5 and State of New York, have invented a new and Improved Belt Buckle, of which the following is a full, clear, and exact description.

The present invention relates to new and 10 useful improvements in separable fasteners, and it pertains more particularly to belt buckles especially adapted for personal wear.

Belt buckles comprising two interengaging members are not new, and such belt buckles are very efficient where the belt is employed for the supporting of garments and the two members of the buckle are under constant strain. Belt buckles of this 15 type, however, are not practical for use as trimming for a garment when no garment-supporting function is involved, and it is one of the primary objects of this invention to construct a belt buckle of this type in such 20 a manner that the interengaged parts will at all times be retained in true or proper interengaged relation.

It is a further object of the invention to construct a belt buckle of the above-mentioned 25 type in such a manner that its interengaged parts although securely held in interengaged relation are capable of ready disengagement for the purpose of opening and closing the buckle.

With the above and other objects in view, 30 reference is had to the accompanying drawings, in which

Figure 1 is a view in front elevation of a 35 buckle constructed in accordance with the present invention;

Fig. 2 is a view in rear elevation thereof; Fig. 3 is a detail sectional view taken on the line 3—3 of Fig. 2;

Fig. 4 is a perspective view of the parts in 40 open interengaged position.

Referring more specifically to the drawings the buckle comprises two members 5 and 6, and each of such members is provided with a strap-attaching eye 7, 8, respectively.

The member 5 is formed with a depressed portion 9 and a cut-out portion forming a substantially T-shaped slot 10. The member 6 has a circular head portion 11 defined

by a flange 12 adapted to seat in the depressed portion 9. The strap-attaching eye 8 of the member 6 is spaced from the head portion thereof by a contracted neck portion 13. The head portion of the member 6 is adapted to be passed through the T-shaped slot and the flange 12, and the member 6 is adapted to be moved downwardly until its flange 12 seats in the depressed portion 9 of the member 5, as shown in Figs. 1 to 3. To secure the two members of the buckle in this position, the depressed portion 9 of the member 5 is formed with a cut-out portion 15 and the flange 12 of the member 6 is formed with a projecting tongue 16 rolled backwardly upon itself as indicated by the reference character 17 to provide a resilient catch member adapted to engage the wall 18 of the cut-out portion 15 to provide a snap catch.

By this construction it is apparent that 75 when the head member 6 is seated with its flange in engagement with the depressed portion 9 of the member 5 and the resilient tongue 16 is passed into engagement with the wall 18 of the cut-out portion 15, the 80 catch serves to secure the two members in position and prevent accidental displacement.

The foregoing construction provides a 85 buckle which will maintain a rigid position without placing the parts thereof under strain, thus rendering the buckle particularly useful in connection with belts used merely as trimmings for garments instead 90 of supports therefor.

What is claimed is:

A buckle, comprising a member having in its outer face a circular depression provided in its bottom with a substantially T-shaped slot and an opening at the peripheral face of the depression, the member being provided with a strap-attaching loop, and a second member having a circular head defined by a flange of a size to fit snugly in the depression of the first member, said member being provided with a strap-attaching loop connected thereto by a neck and on the under face of the flange of its head at the periphery thereof with a resilient catch for 95 engaging the opening of the first member to 100 lock the said members together.

REUBEN SLOTE.
